The ornamental design for a canister exterior for a wet/dry vacuum, as shown and described.

DESCRIPTION

FIG. 1 is a right front perspective view of a canister exterior for a wet/dry vacuum;

FIG. 2 is a front elevational view of the canister;

FIG. 3 is an elevational view of the right side of the canister, the left side of the canister being a mirror image thereof; FIG. 4 is a back elevational view of the canister; FIG. 5 is a top plan view of the canister; FIG. 6 is a bottom plan view of the canister; FIG. 7 is a right front perspective view illustrating the canister with a power head disposed thereon; FIG. 8 is a right front perspective view of a second embodiment of the canister shown in FIG. 1; FIG. 9 is a front elevational view of the canister of FIG. 8; FIG. 10 is a back elevational view of the canister of FIG. 8; FIG. 11 is an elevational view of the right side of the canister of FIG. 8, the left side of the canister being a mirror image thereof; FIG. 12 is a top plan view of the canister of FIG. 8; FIG. 13 is a bottom plan view of the canister of FIG. 8; FIG. 14 is a right front perspective view of a third embodiment of the canister shown in FIG. 1; FIG. 15 is a front elevational view of the canister of FIG. 14; FIG. 16 is a back elevational view of the canister of FIG. 14; FIG. 17 is an elevational view of the right side of the canister of FIG. 14, the left side of the canister being a mirror image thereof; FIG. 18 is a top plan view of the canister of FIG. 14; FIG. 19 is a bottom plan view of the canister of FIG. 14; FIG. 20 is a right front perspective view of a fourth embodiment of the canister shown in FIG. 1; FIG. 21 is a front elevational view of the canister of FIG. 20; FIG. 22 is a rear elevational view of the canister of FIG. 20; FIG. 23 is an elevational view of the right side of the canister of FIG. 20, the left side of the canister being a mirror image thereof; FIG. 24 is a top plan view of the canister of FIG. 20; FIG. 25 is a bottom plan view of the canister of FIG. 20; FIG. 26 is a right front perspective view of a fifth embodiment of the canister shown in FIG. 1; FIG. 27 is a front elevational view of the canister of FIG. 26; FIG. 28 is a rear elevational view of the canister of FIG. 26; FIG. 29 is an elevational view of the right side of the canister of FIG. 26, the left side of the canister being a mirror image thereof; FIG. 30 is a top plan view of the canister of FIG. 26; and, FIG. 31 is a bottom plan view of the canister of FIG. 26. The broken lines are for illustrative purposes only and form no part of the claimed design.
